(57) **CLAIM**

I claim the ornamental design for eyewear, as shown and described.

DESCRIPTION

FIG. 1 is a top view of the eyewear;
FIG. 2 is a bottom view of the eyewear;
FIG. 3 is a side perspective view of the eyewear;
FIG. 4 is a rear view of the eyewear;
FIG. 5 is a front view of the eyewear;
FIG. 6 is a right side view of the eyewear; and,
FIG. 7 is a left side view of the eyewear.

The broken lines shown on the drawings are included for the purpose of illustration only and form no part of the claimed design.
